(No Model.)

W. R. WILLETTS & H. BALL.

ROCK DRILL.

No. 314,897.

Patented Mar. 31, 1885.

UNITED STATES PATENT OFFICE.

WILLIAM R. WILLETTS AND HARRY BALL, OF STAMFORD, CONNECTICUT.

ROCK-DRILL.

SPECIFICATION forming part of Letters Patent No. 314,897, dated March 31, 1885.

Application filed September 22, 1884. (No model.)

To all whom it may concern:

Be it known that we, WILLIAM R. WILLETTs and HARRY BALL, citizens of the United States, residing at Stamford, in the county of Fair-
field and State of Connecticut, have invented
certain new and useful Improvements in Rock-
Drills; and we do hereby declare the following
to be a full, clear, and exact description of the
invention, such as will enable others skilled
in the art to which it appertains to make and
use the same.

Our invention relates to that class of rock-
drills which are operated by steam or com-
pressed air, and has for its objects to so sim-
plify and improve their construction that the
friction and consequent wear of the parts will
be greatly reduced, and a machine produced
which, while economical in cost, shall not be
liable to get out of repair, and will perform a
greater amount of work and with less power
than any machine now in use. With these
ends in view we have devised the simple and
novel construction which we will now describe,
referring by letters to the accompanying draw-
ings, forming part of this specification, in
which—

Figure 1 is a vertical central section of the
cylinder, as on line $x x$, Fig. 3; Fig. 2, an eleva-
tion of the rear cap of the cylinder removed,
showing the ratchet-wheel and spring-pawls;
Fig. 3, an end elevation of the cylinder, show-
ing the feeding mechanism and port-cap, the
plates being indicated in dotted lines; and Fig.
4 a horizontal central section at a right angle
to Fig. 1, as on line $y y$, Fig. 3.

Similar letters indicate the same parts in all
the figures.

A is the cylinder, having a flanged base,
A³, and B the piston, the shape of which is
clearly shown in Figs. 1 and 4.

B' is the piston-rod, and C the upper cap of
the cylinder, which is provided with a recess,
C', to accommodate a ratchet-wheel, O, the
function of which will presently be explained.

D is the lower cap, through which the pis-
ton-rod passes.

E is a rod having spiral grooves, as shown,
which are engaged by corresponding splines
in the recess B' in the piston, as will be more
fully explained.

F is the feed-rod, the yoke or arm which it
engages not being shown.

G is the valve which covers the ports H and
the exhaust H'. This valve is operated by a
rock-shaft, I', to which it is connected by an
arm or rod, I. This rock-shaft is journaled
in a socket formed partially in projection a'
on the cylinder, and partially in plate M, which
is securely screwed or bolted to projection A'.
N is a similar plate, screwed to projection A',
which covers the valve and arm I, forming a
small steam-chest, A², which the steam enters
at A⁴, and then passes to the ports. The rock-
shaft I' is provided with a cross-piece, L, which
is acted on by pins K, which are alternately
lifted by the inclines B³ upon the piston, the
action of said inclines being to tilt or rock
shaft I', which causes valve G to pass from
one port to the other to control the entrance
of steam into the cylinder. It will of course
be understood that the drill itself is attached
in any suitable manner to the piston-rod B'.
The rotation of the drill is accomplished by
means of the spirally-grooved rod E, which en-
gages the piston. This rod is provided with
a ratchet-wheel, O, rigidly secured thereto.

O' indicates spring-actuated pawls, which
engage the ratchet and hold it from turning
backward, so that when the piston moves up-
ward—i. e., toward the right in Fig. 1—the
piston and piston-rod turn upon the grooves
of the spiral rod E; but when the piston moves
downward rod E and the ratchet are free to
turn, so that the blow of the drill is delivered
straight forward. Beyond the ratchet-wheel,
rod E passes through a stuffing-box, P, of any
ordinary construction.

Q is a gear-wheel, loose upon rod E, which
meshes with a gear-wheel, Q', on the feed-rod
F, said rod being free to rotate in the base A³
of the cylinder. This gear is preferably tapped
on a bushing, Q², which is secured to the feed-
rod by a spline or feather, a, so that when gear
Q' is rotated the feed-rod is carried with it.

R is a beveled friction plate or clutch which
slides upon shaft E, and is caused to rotate
therewith by a spline upon the shaft engaging
a groove. (Not shown.)

R' is a knob which is screwed upon the end
of shaft E, forcing the bevel of plate R against
the loose gear Q, thus locking the gear to the
plate and causing it to rotate with shaft E.

The operation is as follows: The power (steam
or compressed air, preferably the former) is

admitted to the steam-chest A² through the pipe shown in Fig. 6, and in dotted lines in Fig. 3, and will rush through one of the ports H. (Shown clearly in Fig. 1.) Suppose that 5 the steam has passed into the cylinder through the right-hand port, (the upper one, when in operative position,) as the piston passes below the middle of the cylinder the right or upper pin, K, begins to travel up the right or 10 upper incline on the piston. This pin, acting on cross-piece L, causes sufficient rotary movement to rock-shaft I' to carry valve G over the upper port, cutting off the entrance of steam into the cylinder above the piston, but allowing 15 it to enter the cylinder at the other port. This raises the piston, the steam in the cylinder above the piston being forced out at the exhaust. The valve continually moves from one port to the other; but the exhaust is continually covered. When the piston is at the 20 upper end of the cylinder, the lower incline on the piston acts on the lower pins to cut off the steam below and to admit it above the piston, these operations being repeated at each 25 stroke of the piston. As the piston moves up rod E, having the spiral grooves, is held stationary by the pawls engaging the ratchet-wheel. This causes the piston to make a partial revolution. As the piston descends it in 30 turn imparts the same amount of rotation to rod E that said rod imparts to the piston during the upward stroke. This movement of rod E carries gear Q with it, provided, of course, that the latter is locked upon the rod. 35 Gear Q meshes with gear Q' upon the feed-rod, turning said rod, which is screw-threaded its entire length. The mechanism for imparting rotation to the feed-rod is wholly new, and of our invention; but motion is communicated by the feed-rod to the cylinder in the ordinary manner, which we have deemed it wholly unnecessary to illustrate—that is, the feed-rod passes through a correspondingly-threaded opening in a yoke or arm (not shown) 40 projecting from the column U. This acts, of course, to raise or lower the drill, according to the direction in which the feed-rod is rotated. At the upper end of this rod a crank (not shown) is always provided. This crank is 45 used to raise the drill, or for a hand-feed when it is not desired to use the automatic feed. As stated above, the automatic feeding mech-

anism is connected or disconnected by means of knob R', which forces the clutch-plate R into engagement with the loose gear Q, thus locking them together. 55

To disengage the automatic feed, it is simply necessary to loosen knob R', which in turn loosens the clutch, thus leaving gear Q loose upon shaft E. 60

We do not desire to limit ourselves to the exact construction shown, as it is obvious that the details may be varied within reasonable limits without departing from the spirit of our invention. 65

Having thus described our invention, we claim—

1. The cylinder and steam-chest having steam and exhaust ports, in combination with a rock-shaft held in place by cap M, and having an arm which carries a valve adapted to slide over said ports, and a cross-piece acted on by pins which are alternately lifted by inclines on the piston, whereby the rock-shaft is vibrated and the valve carried from one 70 port to the other to admit steam alternately above and below the piston. 75

2. The piston, rod E engaging therewith and having a ratchet and pawls to hold it against rotation in one direction, in combination with a gear upon the feed-rod, a loose gear upon rod E, and means, as a sliding clutch-plate keyed to said rod, whereby the loose gear and the gear upon the feed-rod may be connected or disconnected, substantially as 80 85 for the purpose set forth.

3. The feed-rod, free to rotate in the base of the cylinder and carrying a gear Q'; in combination with a recessed piston, a rod, E, having spiral grooves engaging therewith, the 90 ratchet and pawls, a loose gear upon rod E, a sliding clutch-plate held against rotation on said rod, and a knob for forcing the clutch-plate into engagement with the loose gear, whereby the automatic feed may be connected 95 or disconnected.

In testimony whereof we affix our signatures in presence of two witnesses.

WILLIAM R. WILLETTTS.
HARRY BALL.
